US00D584239S

(12) **United States Design Patent**
Bold

(10) **Patent No.:** **US D584,239 S**
(45) **Date of Patent:** **** Jan. 6, 2009**

(54) **BLADE FUSE ELEMENT**

(75) Inventor: **Gary M. Bold**, Palatine, IL (US)

CH 656979 7/1986

(73) Assignee: **Littelfuse, Inc.**, Des Plaines, IL (US)

(Continued)

(**) Term: **14 Years**

(21) Appl. No.: **29/321,736**

(22) Filed: **Jul. 22, 2008**

Related U.S. Application Data

(62) Division of application No. 29/302,292, filed on Jan. 14, 2008, now Pat. No. Des. 575,746.

(51) **LOC (9) Cl.** **13-03**

(52) **U.S. Cl.** **D13/161; D13/173**

(58) **Field of Classification Search** D13/158-184; 439/687; 337/163, 198, 206, 230, 264, 265

See application file for complete search history.

(74) *Attorney, Agent, or Firm*—Bell, Boyd & Lloyd LLP

(57) **CLAIM**

The ornamental design for a blade fuse element, as shown and described.

DESCRIPTION

FIG. 1 is a perspective view of a blade fuse element showing my new design;

FIG. 2 is a front view thereof;

FIG. 3 is a rear view thereof;

FIG. 4 is a side view thereof;

FIG. 5 is a top view thereof; and,

FIG. 6 is bottom view thereof.

The broken line portion of the figure drawings is included to show unclaimed subject matter only and forms no part of the claimed design.

1 Claim, 3 Drawing Sheets
